UNITED STATES PATENT OFFICE.

WILLIAM HEWITT, OF TRENTON, NEW JERSEY, ASSIGNOR TO THE TRENTON IRON COMPANY, OF SAME PLACE.

MACHINE FOR MAKING WIRE ROPE.

SPECIFICATION forming part of Letters Patent No. 358,663, dated March 1, 1887.

Application filed July 20, 1885. Serial No. 112,030. (No model.)

To all whom it may concern:

Be it known that I, WILLIAM HEWITT, a citizen of the United States, residing in Trenton, in the State of New Jersey, have invented certain Improvements in Machines for Making Wire Rope, of which the following is a specification.

My invention relates to a class of devices employed for making continuous ropes or cables of any desired length, a machine embodying my invention being capable, in a single continuous operation, of laying or twisting a number of wires around a strand-core to form a strand, and of laying or twisting a number of strands similarly and as above formed around a main core to form a completed rope or cable. The machine is, moreover, equally applicable for the manufacture of continuous ropes or cables from other material than wires.

The principal object of my invention is the construction of a simple, inexpensive, and automatically operating machine in which wire rope or cable can be made from strands laid or twisted about a main core and composed of individual strand-wires laid or twisted about strand-cores without either the strand-wires or the strand-cores being in the act of laying or twisting subjected to any torsion or twisting with respect to their respective or individual longitudinal axes, and in which a large number of strand-formers can, by reason of their disposition with respect to each other and to the strand-core bobbins in connection with which they operate, be brought within a small diametric or cylindriform compass, in order to permit of the rapid revolution of the machine as an entirety.

Machinery embodying a good form of my improvements is represented in the accompanying drawings, and described in this specification, the particular subject-matter claimed as novel being hereinafter definitely specified.

In the accompanying drawings, Figure 1 represents in elevation, partially, however, sectional, a good form of apparatus embodying my improvements, the section being supposed in the plane of the line $x-x$ of Fig. 5, and sight being taken in the direction of the arrows on said line. Fig. 2 is a central longi-

tudinal vertical and partially sectional fragmentary elevational detail through the main step, the driving and carrying spiders, and the driving-rack, illustrating also the mode of mounting one of the strand-formers of the lower set with respect to the arm of the carrying-spider which supports it. Fig. 3 is a central vertical sectional elevation through the main step. Fig. 4 is a top plan view of the same. Fig. 5 is a top plan view of the machine, the lower strand-formers Nos. 2 and 3 being indicated merely by dotted lines, and the lower strand-former No. 1 being represented in section in a horizontal plane taken through the lower portion of the arms of its tripod-frame, and all of its flier-frames being removed. Fig. 6 is a plan of the carrying-spider and driving spider, section being supposed through the vertical shafts P , and the entire machine above the carrying-spider being removed. Fig. 7 is an elevational view of one of the independent strand-core bobbins, showing also the mode of application of the strand-former which operates in connection therewith. Fig. 8 is a central vertical sectional elevation of the rope-laying head, and Fig. 9 a top plan thereof. Fig. 10 is a side, and Fig. 11 a front, elevation of one of the flier-frames and strand-wire bobbins.

Similar letters of reference indicate corresponding parts.

In the drawings, A represents a main step or hub, which is fixedly erected from a bed-plate or upon the ground. Upon this main step is mounted and about it as a fixed pivot turns what I term a "driving spider," B, the same being a radially-armed or wheel-like contrivance, which is provided with a fixedly-attached annular driving beveled wheel, b , which is stepped upon and has its bearing with respect to said main step A. A beveled pinion, b^* , is engaged with the driving beveled wheel b , and mounted upon a shaft, b^2 , the rotation of which is, through the bevel-gear b^2b^* , imparted to the driving-spider.

C is an annular toothed rack, conveniently supported upon brackets c , so as to be fixed with respect to the earth or the bed-plate, and which encircles the main step, being eccentric

thereto, but concentric with respect to the main shaft E.

D is what I term the "carrying-spider," being a multi-armed spider of substantially the character of the driving-spider B. From it is erected and with it turns the main shaft E, which is tubular. The carrying-spider is mounted by means of a pivot-pin, d, upon the main step A, being, however, eccentric with respect to the vertical axis thereof, so that while both the carrying-spider and driving-spider revolve with respect to said main step, they yet revolve about different pivotal axes.

a is a passage through the main step, which 15 communicates with the hollow interior of the main shaft. Through this passage the main core c^x is led to within the hollow interior of the main shaft.

d^x is a circumferential rim carried by the 20 arms of the carrying-spider, and which rests upon a series of circumferentially-disposed carrying-rolls, H, mounted upon fixed pillow-blocks a, erected from the earth or the bed-plate. The carrying-spider therefore rests 25 upon and revolves with respect to both the main step and the carrying-rolls, and, inasmuch as the entire weight of the various strand-formers and strand-core bobbins is superimposed upon said carrying-spider, it will be 30 obvious that the arrangement is an advantageous one, the weight of said several members mentioned being borne upon solid bearings and taken off the driving-spider.

The carrying-spider and the driving-spider 35 are preferably each provided with the same number of arms. In the drawings I have represented them as each having six arms. Interposed between neighboring arms of the said respective spiders is a series of connecting-links, I, which are respectively provided with fixed depending link wrist-pins i, which are entered within tubular bearings formed in the 40 arms of the driving-spider, and with fixed upwardly-extending link-shafts or spindles i^x, which pass completely through tubular bearings formed in the arms of the carrying-spider, and at a point above said arms are fixedly 45 provided with the yokes J and housings N, which constitute, respectively, the carriers of the strand-core bobbins K and K', whereof 50 hereinafter.

When motion is, through the beveled gearing, imparted to the driving-spider to occasion its revolution with respect to its step, the connection of said driving-spider with the carrying-spider through the connecting-links occasions a revolution of said carrying-spider with respect to its pivot and its carrying-rolls in the same direction and at the same speed as the 60 revolution of the driving-spider. The driving-spider is therefore the motive instrumentality of the carrying-spider.

In the mounting of the machine, all of the connecting-links present or trend in the same direction—that is to say, vertical planes bisecting their respective longitudinal axes are parallel. By virtue of the eccentric disposi-

tion of the said driving and carrying spiders the said parallelism of the links is, moreover, preserved throughout the revolution of both 70 spiders.

Inasmuch, moreover, again, as the carriers J and N of the strand-core bobbins are fixedly connected with the upper extremities of the link-shafts i^x, which latter, as stated, are fixedly connected with or a part of the connecting-links, it is obvious that the said carriers will all trend in a common direction and all maintain a given parallel disposition throughout the revolution of the driving and carrying 80 spiders. As, therefore, the strand-core bobbins which are carried by said carriers or yokes must of necessity maintain the position of their respective yokes, it is obvious that the several strand-core bobbins will all trend in the same direction and maintain their parallel 85 disposition throughout the said revolution of the said spiders. This maintained disposition of the bobbins therefore insures against torsion in the strand-cores k, which are wound upon 90 said bobbins.

It will now be understood in what manner, first, the driving-spider is rotated; second, in what manner the carrying-spider and the main shaft are together rotated, and, third, in what 95 manner the strand-core bobbins, which are disposed upon and carried by the arms of the carrying-spider, are likewise rotated.

Fixedly connected with and rotated by the main shaft are a series of, in the form of machine 100 represented, triarmed horizontally-disposed spiders, which I, for convenience of nomenclature, term the "minor spiders," and of which I designate the lowermost L, the middle D^x, and the upper L^x, the said letters, to avoid 105 unnecessary enumeration, being respectively applied to the several arms which, in fact, compose the said respective spiders. The three arms composing the middle minor spider, D^x, are disposed in line above alternate arms of the six-armed carrying-spider, and between the said three alternate arms of the carrying-spider and the three arms of the middle spider, D^x, are supported, both for revolution about the main shaft and for rotation about 110 their own axes, three strand-formers, Nos. 1, 2, and 3, which contain not only the strand-core bobbins K, but a series of strand-wire bobbins, whereof hereinafter.

The three arms of the upper minor spider, 115 L^x, and the three arms of the lower minor spider, L, are disposed in line above each other, and are, moreover, so disposed that each of the said three arms of each of the said minor spiders, L and L^x, are staggered with respect to or interposed, as regards radial disposition, between the three arms of the middle minor spider, D^x. Between the arms of the upper and lower minor spiders are supported and sustained, both for revolution 120 about the main shaft and for rotation about their own axes, three additional strand-formers, Nos. 4, 5, and 6, which contain a series of strand-wire bobbins—the strand-core bob-

bins K^x , which operate in connection with said last-mentioned strand-formers, not being placed within the circle of their strand-wire bobbins, but being independently supported 5 below the said strand-formers upon the three arms of the carrying-spider, which, in the mounting of the machine, are in line below the arms of the lower minor spider, L , and which alternate with the other three arms of said carrying-spider, which, as already explained, support the three first-mentioned strand-formers.

It is, of course, to be understood that this description is directed to the specific apparatus represented in the drawings, which, as 15 stated, happens to be an apparatus employing six strand-formers and capable of producing six strands only, but that it is perfectly possible to organize a machine operating upon the principle invented by me which shall be 20 provided with a greater or a less number of strand formers than six.

It will now be apparent that there are in the machine under discussion three lower strand-formers, which, for convenience, I designate 25 as Nos. 1, 2, and 3, and three upper strand-formers, which I similarly designate Nos. 4, 5, and 6, and that by reason of the fact that all of the arms of the several minor spiders are of the same length and the arms of the carrying spider, in effect, of the same length, 30 each of the said strand-formers (which, as already explained, are supported between the said spiders) is, as will be understood by a reference to Fig. 5, at the same radial distance from the main shaft, although with regard to circumferential disposition the said 35 three lower strand-formers, 1, 2, and 3, alternate with the three upper strand-formers, 4, 5, and 6.

40 Inasmuch as the three minor spiders are fixedly connected with the main shaft and the main shaft fixedly connected with the carrying-spider, the revolution imparted to the latter, in the manner hereinbefore explained, will 45 occasion the revolution of all the strand-formers with respect to the vertical axis of the main shaft, the said revolution being that necessary to bring to pass the laying or twisting of the strands formed, as hereinafter explained, 50 in the respective strand-formers about the main core, which is carried up through the main shaft.

As all of the strand-formers are of the same construction, a description of one will suffice 55 for all.

The strand-formers represented are each provided with twelve strand-wire bobbins, so as to be adapted to lay twelve strand-wires, k' , about a strand-core, k , to form a strand, k .

60 Each strand-former is composed, essentially, of a rotatable housing or frame-work for sustaining the strand-wire bobbins. I prefer to form these housings in the following manner:

F are "flier-spiders," as I have termed 65 them, provided with a number of arms corresponding with the number of strand-wire bobbins employed. In the drawings the flier-

spiders shown have each twelve arms to support twelve strand-wire bobbins. Each flier-spider F supports what I term a "tripod-frame," G , which sustains a hollow vertical strand-former shaft, g , the upper extremity of which is journaled in an arm of a minor spider and provided with a strand-laying head, g' . The three strand-formers of the upper set have 70 each a lower bearing, l , in the arms of the lower minor spider, L , which bearing is represented in Fig. 7, the flier-spiders turning freely upon the axially-apertured hub of a horizontal beveled rack, M , secured to the housing N 75 of the three independent strand-core bobbins K^x , which operate in conjunction with the upper set of strand-formers, and which, as already stated, are respectively intermediate between the three strand-formers of the lower 80 set. The strand-cores k , which are carried upon the independent strand-core bobbins K^x , are led up through the axial apertures of the beveled racks M , and thence up and through the strand-former shafts g to the strand-laying 85 heads g' , which each contain a die similar to that carried by the rope-laying head.

The flier spiders of the three strand-formers constituting the lower set turn freely upon the link shafts i^x and rest upon the horizontal 90 beveled racks M^x , which are fixedly connected with said link-shafts, all as represented in Fig. 2.

The tripod-frame of each strand-former housing is conveniently equipped with a circular ring, g^x , which sustains the upper bearings of the radially-disposed series of flier-frames, carriers, or revoluble housings f , for carrying the strand-wire bobbins O , the lower 100 bearings of which are formed in the respective arms of the flier-spiders or in any ring or kindred contrivance connected therewith or carried thereby.

105 Each of the flier-frames of the strand-wire bobbins is preferably inclined inwardly from the vertical, as represented in the drawings, so that the various strand-wires k' led from the strand-wire bobbins O will pass in a direct line through the upper hollow journals, f^x , of the flier-frames up to the strand-laying heads g' , with which the strand-formers are, as stated, 110 respectively provided.

115 In order to effectuate the laying or twisting of the strand-wires about the strand-cores, it is of course essential to revolve the strand-formers about their respective axes, and this I accomplish by providing a series of vertical shafts, P , preferably corresponding in number with the number of strand-formers, and journaled in boxings p , respectively formed in the 120 minor and carrying spiders, which shafts, for the accommodation of the eccentric movement thereof, pass freely through circular openings b^x , formed in the driving-spider, and are below said driving-spider equipped with driving pinions p^x , which engage with the fixed annular toothed rack C . It is obvious that as the carrying-spider is revolved the said driving pinions p^x will be rotated by their revolutionary

engagement with the said fixed rack, which latter, as stated, is concentric with the axis of rotation of the carrying-spider, and that therefore all of the shafts will be rotated.

5 Three of the shafts have vertical extension to the upper minor spider, and three of them but to the middle minor spider. The three longer shafts are employed to occasion the revolution about their own axes of the three upper strand-formers. The three shorter shafts are employed for a similar purpose in connection with the three lower strand-formers.

Each vertical shaft P is at its upper extremity provided with a driving toothed wheel, p' , which, through the intervention of idler toothed wheels p'' , p''' , journaled upon the minor spiders, occasions the rotation of a driven toothed wheel, p^4 , conveniently mounted upon the strand-former shaft g of the particular strand-former in connection with which said train of toothed wheels operates, and thereby occasions the revolution of the strand-former about its own axis.

25 It will now be understood in what manner the strand-formers are revolved about the main shaft, and also in such revolution revolved about their own axes.

I have heretofore mentioned the importance of avoiding torsion in the strand-wires. In order to such avoidance it is essential that the strand-wire bobbins, which are grouped radially and revolvable about or with respect to the strand-core bobbins, should be so controlled that they shall always throughout their revolution about the axis of the strand-formers which contain them bear a predetermined directional relationship to said strand-core bobbins, and consequently also to the points of the compass. 35 This result I accomplish by prolonging, preferably, the lower journal, f^1 , of each flier-frame f , below its bearing in the arm of the flier-spider which carries it, and providing the prolonged extremity with a worm-wheel, f^2 , which is adapted to be engaged with a worm-thread, f^3 , upon the outer extremity of a flier-shaft, f^4 , journaled in radial disposition with respect to the housing in the strand-former, the other extremity of which shaft is 45 provided with a beveled pinion, f^5 , which is engaged with the teeth of the fixed beveled racks M or M' , as the case may be.

The relationship between the worm-wheel on the flier-frame, the worm-thread on the 55 flier-shaft, the pinion on said shaft, and the fixed beveled rack is intentionally such, and it is a matter simply of mathematical calculation and proper proportioning of parts that each flier-frame, and consequently the strand-wire bobbin with which said frame is provided, maintains the same directional relationship 60 with respect to the strand-core bobbin operating in connection with the strand-former of which the frame under consideration is a member, and consequently with respect to the points of the compass throughout its entire revolution about the axis of said strand-former, whereby

each particular strand-wire is presented to its strand-laying head without torsion. Thus, to describe, in other words, the relation between 70 the pinion on the flier-shaft and the fixed beveled rack which drives it is inversely the same as the relation between the worm-thread on said shaft and the worm-wheel on the flier, the rack, for instance, being to the pinion as 75 twelve is to one, and the worm-wheel being to the worm-thread as twelve is to one.

It is of course obvious that it is inconsequential in what position the flier-frames and their contained bobbins are originally set, as 80 they must necessarily maintain their individual directional relationship to the points of the compass throughout their individual revolutions about the axis of the strand-former of which they are members. Thus, therefore, 85 torsion of the strand-wires is completely avoided whether the said strand-wire bobbins of given strand-formers be all, as represented in Fig. 5, originally set with their shafts parallel, or whether, as represented in 90 Fig. 1, the several strand-wire bobbins of the same strand-former are originally set with their shafts at varying angles.

The flier-frames f are all of the same construction, and are especially illustrated in 95 Figs. 10 and 11. The strand-wire bobbins O , which these frames contain, are mounted upon shafts O^1 , which are removable and conveniently held in place by a spring-actuated bolt or pin, O^2 , as shown in Fig. 11.

The strand-wires and strand-cores are put under tension by means of a tightening strap or cord, O^3 , applied to both the strand-core bobbins and the strand-wire bobbins, by being passed around a suitable tension disk or drum, O^4 , which is a part of or connected with said bobbins, and which cord is adapted to be tightened by means of tightening thumb-nuts O^5 , or kindred contrivances connected therewith and applied to the housings or frames of the several bobbins, as especially illustrated in 100 Figs. 7, 10, and 11. Instead, however, of the foregoing tension device, any other device adapted to control the too-ready unwinding of the bobbins and applied to said bobbins may be 115 employed.

As already mentioned, the three strand-formers constituting the lower set are provided with strand-core bobbins which are housed within the frame-work, frame, or housing of said strand-formers, as a reference to Figs. 1 and 2 will make clear, while the three strand-formers which constitute the upper set operate in conjunction with independent strand-core bobbins which are supported direct upon the carrying spider and axially below the said strand-formers. All of the said strand-core bobbins are, however, connected with the link-shafts of the connecting-links in the manner already fully explained. The object of this arrangement is to avoid lifting the heavily-laden strand-core bobbins higher than is actually necessary, and to translate the weight of such strand-core bobbins directly to

the carrying spider and as low down as possible in the machine. Incidentally, moreover, this arrangement permits of the bringing of the entire machine within a smaller compass, so that a greater number of revolutions per minute can be obtained.

R is what I term a "head-boxing," conveniently composed, as represented in Fig. 8, of a top plate, t , a bottom plate, t' , a yoke-plate, t'' , all preferably of metal, and of a rectangular frame, t''' , erected upon the yoke-plate and supporting the top plate. The bottom plate is surmounted upon and connected with the upper extremity of the tubular main shaft 15 E, and it is provided with a series of converging apertures, t''^* , through which the strands k^* pass to a central aperture, t' , in the top plate. The head-boxing as above constructed is, as will be apparent from a reference to Fig. 8, a 20 box-like contrivance, although, as is obvious to any mechanic, the form in which it is made may vary. The head-boxing carries a sectional or other die, r , which is conveniently contained in a die-yoke, r'' , supported upon 25 vertical bolts r' , which are adjustable within transverse slots r''^* , formed in the head-boxing, and which also pass through slots formed in the die-yoke. By means of this arrangement the die itself can be adjusted in any direction 30 with great nicety.

Traction is, of course, exerted upon the main core and the various strands to draw them, when laid together as a completed cable, through said die, the rapidity of traction measurably determining the amount of twist both 35 in the rope and in the strands. The strand-laying heads are conveniently made of substantially the same construction as that described with reference to the rope-laying head.

Having now described a good form of apparatus embodying my invention, and sufficiently, also, the operation of the same, it is proper for me to add that the strand formers are conveniently geared in such manner as to 45 make about four revolutions upon their own axes to one revolution about the main shaft. The strand-wire bobbins revolve around or with respect to the strand-core bobbins at a rate of speed which may be adjusted independently of the speed of revolution of the strand-core bobbins about the main shaft.

As will be perceived, the machine is adapted to make any of the usual kinds of rope.

The strand cores, which are made outside of 55 the machine and wound upon the strand-core bobbins, which are then applied to the machine, may be either single wires or cords, about which six wires may be laid to form a seven-wire-strand rope; or the strand-cores 60 may be of three wires previously twisted together, about which nine wires may be laid to form a twelve-wire rope, or the strand-cores may be of seven wires previously twisted together, (six laid around one,) about which 65 twelve wires may be laid to form a nineteen-wire-strand rope; or the strand-cores may be of seven wires twisted together, about which

six seven-wire strands may be laid to form a "strand-rope," as it might be called, six such strand-ropes being then laid together to form 70 a larger rope.

It is preferable to drive the strand-formers from above rather than from below, the mode represented in the drawings being a good one. Other means, however, of imparting rotation 75 to said strand-formers may, if desired, be resorted to.

It is apparent that the principle of the link-connection illustrated and described herein as applied to the strand-core bobbins, for 80 the maintenance of their given directional relationship throughout their revolution, may, by a very simple modification, be applied to the fler-frames of the strand-wire bobbins of each of the strand-formers, so that the said 85 strand-wire bobbins may be each preserved in given directional relationship throughout its revolution about its strand-former by a link-and-spider connection rather than by the connection of gearing represented and described. 90

It is, moreover, manifest that many mechanical contrivances other than the compound spider B D may be resorted to for securing the revolution of the machine as an entirety.

Having thus described my invention, I 95 claim—

1. The combination of a central and revolvable main shaft, means for operating said main shaft, a lower series of strand-formers radially disposed at predetermined distances apart 100 around said shaft and supported from said shaft near its base, and each composed of a revolvable open-centered frame containing a series of radially-disposed fler-frames for carrying strand-wire bobbins, a first series of 105 yokes or carriers for a series of strand-core bobbins, each disposed within the open center of the revolvable frame of a given former of said aforesaid lower series of strand-formers, and each directly surrounded or encompassed by the fler-frames of said strand-former of said lower series, an upper series of 110 strand-formers radially disposed at predetermined distances apart around said shaft, supported therefrom upon a level higher than 115 that of the lower series, alternating with regard to circumferential distribution with the strand-formers of said lower series, and each composed of a revolvable frame containing a series of radially-disposed fler-frames for carrying strand-wire bobbins, and a second series 120 of single or separate and independent yokes or carriers for strand-core bobbins corresponding in number with the strand-formers of the said upper series in line below said 125 formers, but not centrally disposed therein, and upon the level of the strand-core bobbin-carriers of the first series of carriers, which are disposed within the centers of and operate in conjunction with the lower series of 130 strand-formers, substantially as and for the purpose set forth.

2. The combination, with a main shaft, of two series of strand-formers supported from

5 said shaft, grouped around it on different levels, and successively alternating or staggered, a series of separate and independent carriers for strand-core bobbins, corresponding in number and in radial disposition with the several strand-formers, together composing the said two series, but all placed upon a common level, being substantially that of the lower of the 10 two series of strand-formers, and means, substantially such as set forth, for preserving in said carriers for said strand-core bobbins a given directional relationship throughout their revolution, substantially as and for the purposes set forth.

15 3. The combination of a revoluble main shaft provided with a rope laying head and 10 a series of fixed-armed spiders for supporting strand-formers, a step or base-pivot upon which said shaft is erected and rotates, a 20 driving-spider operating eccentrically with respect to said shaft and the fixed spiders, means for rotating said driving-spider, connecting-links between the driving-spider and one of the spiders carried by the shaft, a series of 25 strand-formers connected with and carried by the fixed spiders, and a series of carriers for strand-core bobbins, connected with the connecting-links aforesaid, substantially as and for the purposes set forth.

30 4. The combination, with a revoluble vertical main shaft, of a basal or carrying spider or frame formed with a peripheral rim, a series of minor spiders upon said shaft at intervals above said basal spider, a series of strand-form-

ers supported by the respective spiders substantially in the manner set forth, a series of carriers for strand core bobbins the weight of all of which is superimposed upon the basal spider, and means for supporting the peripheral rim of said basal spider and permitting the revolution thereof, substantially as set forth.

5. The combination of a revoluble main shaft having a rope-laying head, a carrying-spider secured to and concentric with said main shaft and revolving with it about the same axis of revolution, a series of minor spiders connected with said main shaft, a series of strand-formers supported by said spiders and grouped about and revoluble with the main shaft substantially in the manner set forth, a driving spider the axis of the revolution of which is eccentric to that of the main shaft, means for revolving said driving-spider, connecting-links provided with link wrist-pins 55 boxed in the driving-spider and with link-shafts passing through the carrying-spider, and carriers for strand-core bobbins fixedly connected with said link-shafts and superimposed upon said carrying-spider, substantially as set forth.

In testimony whereof I have hereunto signed my name this 10th day of July, A. D. 1885.

WM. HEWITT.

In presence of—
J. BONSALL TAYLOR,
JOHN JOLLEY, Jr.

Correction in Letters Patent No. 358,663.

It is hereby certified that in Letters Patent No. 358,663, granted March 1, 1887, upon the application of William Hewitt, of Trenton, New Jersey, for an improvement in "Machines for Making Wire Rope," an error appears in the printed specification requiring correction, as follows: In line 23, page 2, the reference letter "a" should read *h*; and that the Letters Patent should be read with this correction therein that the same may conform to the record of the case in the Patent Office.

Signed, countersigned, and sealed this 8th day of March, A. D. 1887.

[SEAL.]

D. L. HAWKINS,
Acting Secretary of the Interior.
